UNITED STATES PATENT OFFICE.

LEWIS A. CARPENTER AND RICHARD MIDDLETON, OF REVERE, MASSACHUSETTS.

TWO-PIECE PIPE-HANGER.

1,111,360.

Specification of Letters Patent. Patented Sept. 22, 1914.

Application filed May 7, 1913. Serial No. 766,039.

To all whom it may concern:

Be it known that we, LEWIS A. CARPENTER and RICHARD MIDDLETON, citizens of the United States, residing in Revere, in the 5 county of Suffolk and State of Massachusetts, have invented an Improvement in Two-Piece Pipe-Hangers, of which the following description, in connection with the accompanying drawings, is a specification, like 10 characters on the drawings representing like parts.

This invention relates to a pipe hanger and has for its object to provide a sheet metal hanger of two pieces, which is light, 15 strong, inexpensive, attractive, and ornamental in appearance. For sake of distinction the two members of the hanger may be designated the base member and the cap member. The base member is designed to be 20 applied to the wall, ceiling or other support, and comprises a hollow body portion having a substantially central semicircular recess extended from the front wall of the base toward the back thereof, for the reception 25 of substantially one half of the pipe to be supported, and to which front wall is secured the cap member, having a substantially semicircular recess which co-operates with the recess in the body portion. The 30 front wall of the base is provided on opposite sides of the recess with substantially flat portions, which are engaged by the substantially flat ears of the cap. The base member may be secured to the wall or other support 35 by a screw extended through an opening in the wall of the recess in said base member. These and other features of this invention will be pointed out in the claims at the end of this specification.

40 Figure 1 shows an elevation of a pipe hanger embodying this invention. Fig. 2, a vertical longitudinal section. Fig. 3, a plan of the base member inverted, and Fig. 4, a section on the line 4—4, Fig. 2.

45 Referring to the drawing *a* represents the hollow base member, and *b* the cap member of a pipe hanger embodying this invention. The hollow base member *a* is struck up from a single piece of sheet metal to form a 50 hollow body portion 10, which is open at its rear side and closed at its front side. The body portion 10 is provided with a central substantially semicircular recess, whose bottom wall 12 forms part of the front wall of 55 the hollow base, which front wall is pro-

vided on opposite sides of the recess with substantially flat portions 13, 14.

The body portion 10 may and preferably will be provided at its rear side with an outwardly extended flange 15 integral therewith. The body portion 10 may and preferably will be made substantially oval in cross section and also tapering from the rear side to the front side. The cap member *b* may and preferably will be made of sheet metal 60 and is concaved transversely and provided with a substantially semicircular recess, which co-operates with the recess in the base member for the reception of the pipe *d*, and said cap member is provided with ears 17, 18, 65 which engage the flat portions 13, 14 of the front wall of the hollow base member, and are secured thereto by the screws 19, 20.

The wall 12 of the recess in the hollow base member is provided with a countersunk portion 21, for the reception below the bottom of the recess of the head of the screw 22, by which the hollow base member is secured to the wall, ceiling or other support 70

75 The flat portions 13, 14 of the front wall of the hollow base member are provided with openings 24, 25, whose walls 26, 27 are extended into the hollow base and are screw threaded to be engaged by the screws 19, 20.

80 The pipe hanger herein shown and described is light, strong, inexpensive and pleasing in appearance. The oval and tapering form of the hollow body portion imparts the necessary strength to enable thin sheet metal stock to be used, and the front or outer ends of the walls of the body portion are braced by the front wall which is integral therewith.

Claims.

95 1. A pipe hanger comprising a sheet metal base member having a hollow body portion open at its rear end and provided at its front end with a wall to close said body portion and having a recess for the reception of a pipe and substantially flat portions on opposite sides of said recess, the bottom wall of the latter having a countersunk opening, and a sheet metal cap member having a recess and substantially flat ears on opposite sides thereof, and means to secure said ears 100 to the flat portions of the end wall of said base member, substantially as described.

105 2. A pipe hanger comprising a sheet metal base member having a hollow body portion open at its rear end and provided with an 110

outwardly extended flange, said body portion having side and end walls tapering from the rear of said body portion toward its front end and provided with a front wall 5 separated from the rear end of said body portion and having a recess for the reception of a pipe and substantially flat portions on opposite sides of said recess, and a cap member having a recess for the reception of the 10 pipe and ears on opposite sides thereof, and means to secure said ears to the flat portions of the front wall of said base member.

3. A pipe hanger comprising a one piece sheet metal base member having a hollow body portion open at its rear end and provided at its front end with a wall separated from the rear end of the body portion and

having a substantially semicircular recess for the reception of a pipe and substantially flat portions on opposite sides of said recess 20 and having side and end walls, and a cap member having a recess for the reception of the pipe and ears on opposite sides thereof, and means to secure said ears to the flat portions of the front wall of said base member, 25 substantially as described.

In testimony whereof, we have signed our names to this specification in the presence of two subscribing witnesses.

LEWIS A. CARPENTER.
RICHARD MIDDLETON.
